UNITED STATES PATENT OFFICE

WILLIAM H. STARING, OF WILLOUGHBY, OHIO, ASSIGNOR TO AUTOMATIC REGISTERING MACHINE COMPANY, INC., A CORPORATION OF NEW YORK

VOTING MACHINE

Application filed October 28, 1926. Serial No. 144,838.

This invention relates to an improvement in voting machines, and more particularly in voting machines of the type shown in the patent to Lausterer, No. 1,189,837, in which the votes are recorded by counter mechanism, which is in a compartment at the back of the voting machine, closed by a door.

Prior to this invention, when the polls are closed the door to the compartment is opened, and the result shown by the counter mechanism is noted. When the compartment is thus open the counter mechanism is unprotected, and the primary object of this invention is to avoid this by providing means which guard it, while it is being inspected for the purpose of ascertaining the vote.

Another object of this invention is to provide means necessitating the complete protection of the counters before the voting machine can be locked by the custodian.

A further object of this invention is to provide means for covering the custodian's lock, which means cannot be removed without immediate detection.

Other objects of this invention will appear from a consideration of the following description taken in connection with the drawings which form a part thereof, and in which

Fig. 1 illustrates an elevation of the rear of a voting machine equipped with this invention;

Fig. 2 is a sectional view thereof;

Fig. 3 is an enlarged detail, showing certain mechanism; and

Fig. 4 is a perspective view of another part of the mechanism.

The counter mechanism in the compartment at the rear of the machine includes a panel 10, through which the dials of a plurality of counters 11 are exposed. It will be understood, of course, that during the operation of the machine these dials are actuated so that an examination of the counters 11 will disclose the number of votes cast for each candidate.

Mounted in channels 12, 13, in front of the panel 10 are a pair of glass plates 15, through which the counters 11 can readily be observed, and by which the counters are fully protected. When the machine is being

prepared for voting the plates 15 are slid in the channels 12, 13, to allow the election officers to set the counters back to zero.

Fixed upon and depending from a shelf 16, on which the channels 12, 13 rest is a bracket 17 having a vertical slot 18 therein. An angle plate 19 is secured to the bracket 17 by a pin 20, which extends through the slot 18, thus permitting the reciprocation of the angle plate with reference to the bracket. Pins 21, 22, mounted on the upper arm of the angle plate 19, project through apertures 23 into the channels 12, 13, the pin 21 entering the outer channel 13 and the pin 22 entering the inner channel 12.

Obviously, when the plates 15 are closed and the angle plate 19 is in the raised position, the pins 21, 22 in front of the plates prevent their movement in one direction. The movement of the plates 15 in the other direction is prevented by covers 24, which close the spaces between the plates 15 and the side walls of the casing 25. Thus, when the covers 24 are in place and the pins 21, 22 are raised the glass plates cannot be moved in either direction.

Below the counter compartment just described is a compartment closed by a door 26 which is mounted to swing upwardly on hinges 27. The door 26 is secured in the closed position by a key actuated lock 28, customarily referred to as the custodian's lock. This is the final lock for the machine, the key for which is customarily held by the custodian of the election or the chief clerk, and is not in the possession of the election officers at the booth.

In order to insure the locking of the glass plates 15 the reciprocable plate 19 is provided with an offset flange 29, having an opening 30 therethrough. On the rear face of the door 26 is fixed a stud 31, which, when the door is closed and the plate 19 is raised, will enter the aperture 30. When, however, the plates 15 are open the pins 21, 22 will be under the plates, and hence the angle plate 19 will be depressed, so that the stud 31 will strike against the flange 29, and thus prevent the closing of the door 26 until the plates 15 are closed and the plate 19 raised.

As a further protection to the lock 28, a plate 32 is pivotally mounted at 33, on the door, which plate, when in its upright position will completely cover and protect the key hole 34 of the lock. A flange 35, bent upwardly from the plate 32, is provided with a slot 36, through which a pin 37 carried by the door 26 projects. When the cover plate 32 has been raised over the keyhole 34, the pin 37 will project through the slot 36 in the flange 35. The plate 32 is fixed in this position by a wire passed through a hole 38 in the pin 37, and provided with a seal 39. Obviously, therefore, before the glass plates 15 can be moved from their protecting positions, the seal 39 must be broken and the lock 28 unlocked, so that the door 26 can be opened and the plate 19 lowered.

Hence, in a voting machine embodying this invention, when the compartment is opened for an inspection of the counters 11 the plates 15 permit a free inspection, while at the same time they prevent an unauthorized handling of the counters. Moreover, not until the seal 39 has been broken and the lock 28 unlocked by the custodian can the plates 15 be moved and the counters reached.

The lower channels 12 and 13 are made in two sections, those at the right designated as 12a and 13a being removable in order to permit the insertion or removal of the glass plates 15. The sections 12a and 13a are secured in place by pins 40, rigidly fixed to the underside of the sections by riveting or other means, which pins 40 project through apertures 41 suitably located in the shelf 16.

While one embodiment of this invention has been shown and described, applicant is not limited thereto, since it is obvious that other embodiments can be made without departing from the spirit and scope of this invention as set forth in the following claims.

Having thus set forth my invention what I claim as new and for which I desire protection by Letters Patent is:

1. In a voting machine having a compartment, channels fixed in and adjacent one wall of said compartment, plates slideable in said channels, and reciprocable pins in said channels, which pins in one position permit and in another position prevent the movement of said plates, when said plates close said compartment.

2. In a voting machine having a compartment, channels fixed in and adjacent one wall of said compartment, plates slideable in said channels, an angle plate slidably mounted in said machine below said channels, pins fixed on said angle plate, said channels having apertures through which said pins project when said angle plate is raised to prevent the movement of said plates in said channels, when said plates close said compartment.

3. In a voting machine having a plurality of compartments, means for closing both said

compartments, and means including a plate and a plurality of pins, preventing the closure of one compartment until the other compartment is closed.

4. In a voting machine having a plurality of compartments, channels in one of said compartments, and plates slideable in said channels to close said compartment, a door to close the other of said compartments, and means to prevent the closing of said door until said plates close said first named compartment.

5. In a voting machine having a plurality of compartments, channels in one of said compartments, and plates slideable in said channels to close said compartment, a door to close the other of said compartments, and slideable means including an angle plate and a plurality of pins to prevent the closing of said door until said plates close said first named compartment.

6. In a voting machine having a plurality of compartments, channels in one of said compartments, and plates slideable in said channels to close said compartment, a door hinged to said machine to close the other of said compartments, and means preventing the closing of said door when said slideable plates are open.

7. In a voting machine having a plurality of compartments, channels in one of said compartments, and plates slideable in said channels to close said compartment, a door hinged to said machine to close the other of said compartments, and means actuated by said plates to prevent the closing of said door when said slideable plates are open, said means also locking said plates closed when said door is closed.

8. In a voting machine having a plurality of compartments, channels in one of said compartments, and plates slideable in said channels to close said compartment, a door hinged to said machine to close the other of said compartments, and means preventing the closing of said door when said slideable plates are open, and locking said plates closed when said door is closed, said means including a plate slidably supported by said channel, and a plurality of pins.

9. In a voting machine having a plurality of compartments, channels in one of said compartments, and plates slideable in said channels to close said compartment, a door hinged to said machine to close the other of said compartments, and means preventing the closing of said door when said slideable plates are open, and locking said plates closed when said door is closed, said means including a plate slidably supported by said channel, a plurality of pins on said plate and a pin on said door, which enters an aperture in said plate.

10. In a voting machine having a plurality of compartments, channels in one of said

compartments, and plates slidable in said channels to close said compartment, a door hinged to said machine to close the other of said compartments, and means preventing the closing of said door when said slidable plates are open, and locking said plates closed when said door is closed, said means including a bracket depending from said channels, a plate slidably supported by said bracket and provided with an aperture, pins fixed on said plates to project through apertures in said channels in front of said sliding plates, and a pin on said door which enters the aperture in said plate, when said plate is raised, and said pins project into said channels to prevent movement of said plates.

In testimony whereof I have affixed my signature.

WILLIAM H. STARING.
